UNITED STATES PATENT OFFICE.

ALLEN F. WILSON, OF CLAYTON, NEW JERSEY, ASSIGNOR OF ONE-HALF TO
JOHN WESLEY WEBB, OF CLAYTON, NEW JERSEY.

IMPLEMENT FOR FINISHING NECKS AND LIPS OF BOTTLES.

SPECIFICATION forming part of Letters Patent No. 692,957, dated February 11, 1902.

Application filed October 1, 1901. Serial No. 77,206. (No model.)

To all whom it may concern:

Be it known that I, ALLEN F. WILSON, of Clayton, in the county of Gloucester and State of New Jersey, have invented a new and useful Improvement in Implements for Finishing the Necks and Lips of Bottles, of which the following is a specification.

This invention relates to the necks of bottles, and particularly that class of bottles which are closed by a cap engaging in screw-threads formed externally on the neck and making a tight closure by drawing down a disk of cork or like packing into contact with the lip or end of the bottle-neck; and my invention has for its object the production of segmental projections on the neck accurately true with the lip of the bottle and having the bottle-lip with a fire-finished surface without requiring any grinding or other finishing operation to fit it for use; and to this end my invention consists of a rotatable mold adapted to form segmental projections on the bottle-neck combined with a tapering fluted plug and a pair of contractible and expansible jaws which by their operation finish the bottle-lip and the neck and segmental projections thereon with a perfection of accuracy not heretofore obtainable.

Heretofore in making segmental projections upon the necks of glassware it has been the common practice to form them by the process of blowing them in lengthwise-partible molds and afterward severing the neck from the blowpipe and grinding the lip of the neck so as to adapt it to fit a packing or cover. This involves expense and is not accurate in its resulting shape, besides leaving a rougher surface, which abrades the packing or cork in the cap. By the use of my implement I secure an accurate form of lip in relation to the segmental projections and have a fire-polished surface upon the lip, which does not abrade the cork or other packing, and such bottle-necks are of such uniform dimensions and form that they can be used interchangeably with suitable caps of uniform size without requiring any adjustment of packing to fit each neck and lip, as was required in the mold-blown and ground bottles. My invention is shown in the accompanying drawings, in which—

Figure 1 shows a side view of my improved tool; Fig. 2, an edgewise view thereof; Fig. 3, a lengthwise central section thereof; Fig. 4, an end view of the tapering plug; Fig. 5, 55 an end view of the mold, and Fig. 6 a detached view of the guide for holding the mold and jar in proper alinement with each other.

Referring to the drawings, *a a* represent the shanks of the tool, united at the rear end 60 by a bowed spring *b* and provided with wooden covers or handles *c c*. The front ends of the shanks *a a* terminate in jaws *d d*, provided with grooves *e e*, which correspond with the bead formed on the bottle-neck. 65

f is a guide having stems *g g*, which pass freely through openings *h h* in the shanks *a a* and guide the shanks *a a* and jaws *d d* in parallel position in their opening and closing movements. Nuts *i i* are placed on the ends 70 of the stems *h h* to restrict the opening motion of the shanks *a a* and jaws *d d*.

A mold *j* is secured rotatably upon the guide *f*, in which mold there are formed segmental recesses *k k k* of the form of the desired projecting segments on the bottle-neck. The guide *f* and mold *j* are held in central position and alinement by a stem *m*, passing through the spring *b*, and are adjusted lengthwise by nuts *n n* on the screw-threaded end of 85 the stem *m*. In the center of the mold *j* is placed a fluted tapering stem or projecting plug *o*, which is inserted in the guide *f* and has a collar *p* formed on it, which acts as a bottom of the mold *j*. The jaws *d d* have shoulders *q q* 85 formed in them, which when closed fit over the rim of the mold *j*. The position of the mold *j* in relation to the jaws *d d* is adjusted by means of the nuts *n n*, so as to be close to the edge of the mold, but not to touch the 90 mold, so as to impede its rotation.

The implement is used and operated in the following manner: The workman places a heated bottle held by the bottom, so as to rotate it, and inserts the plug *o* in the neck and 95 inserts and forces the end of the neck in the mold, holding the jaws into a closed position against the neck. The rotation of the bottle on the stem *m* expands the soft glass into the mold and shapes the neck to conform to the 100 shape of the interior of the mold, and the jaws, closing against the bottle-neck as it rotates,

smooths the neck and reduces it to the diameter of the portion in the mold *j* and forms a bead upon the neck in the grooves *e e*. The end pressure exerted by the workman upsets 5 the material of the neck, causing it to fill the mold, and leaves a lip or end to the neck exactly true in relation to its axis and length with the segments formed in the neck. Upon 10 opening the implement by relaxing the grasp on the handles the bottle-neck is liberated and discharged from the mold.

Having described my invention, what I claim is—

1. In a tool for finishing bottle-necks with 15 external segmental projections thereon, a rotatable mold adapted to inclose the end of the bottle-neck having segmental recesses opening to the rim of the mold in combination with expansible and contractible jaws 20 and connected handles for holding said jaws in closed position over the mold and bottle-neck substantially as set forth.
2. In a tool for finishing bottle-necks a ro-

tatable mold adapted to surround the neck of a bottle and having recesses therein for mold- 25 ing projections on the bottle-neck, a tapering non-rotatable fluted plug in combination with shouldered jaws adapted to close over the mold and connected handles for opening and closing said jaws as set forth.

3. In a tool for finishing bottle-necks and forming segmental projections thereon, a rotatable mold adapted to surround the neck of a bottle and having segmental recesses open 35 to the edge of the mold in combination with expansible and contractible jaws having shoulders fitting over the edge of the mold, shanks and handles and a spring uniting said shanks, and a stem and guide controlling the position of said mold and jaws arranged to 40 operate as set forth.

ALLEN F. WILSON.
